[57] CLAIM

The ornamental design for an equestrian stirrup iron, as shown and described.

DESCRIPTION

FIG. 1 is a reduced perspective view of an equestrian stirrup iron showing my new design;
FIG. 2 is a top plan view thereof;
FIG. 3 is a front elevational view, the rear elevational view being a mirror image;
FIG. 4 is a right side elevational view, the left side elevational view being a mirror image;
FIG. 5 is a bottom plan view thereof; and
FIG. 6 is another perspective view thereof with the top portion rotated 90° from the position of FIGS. 1-5.

1 Claim, 2 Drawing SheetsFIG. 2.

FIG. 1.

FIG. 3.

FIG. 4.

FIG. 5.

FIG. 6.
